2,152,432

DEVICE FOR WARP LEASING

Frank H. Kaufmann, Elkins Park, Pa., assignor
to Steel Heddle Manufacturing Company,
Philadelphia, Pa., a corporation of Pennsyl-
vania

Application August 25, 1937, Serial No. 160,766

12 Claims. (Cl. 28—40)

This invention relates to a device for warp leasing, and it has particular relation to novel means for effecting the separation of the warp threads to permit the insertion of lease cords or rods which are used to maintain an orderly arrangement of the warp threads, usually at the beginning and ending of the warp. The formation of such leases in a warp facilitates the drawing in or laying in the warp in a reed or comb, and, in some instances, the entering of the warp through the harness of a loom.

The present invention is more particularly adaptable for use in the formation of what are known as "pin leases", that is to say, where the lease is so formed that the threads are separated in sets, one set for each dent space of the reed of the loom in which the warp is subsequently to be mounted, although, of course, it should be understood that the device may, under certain conditions, be used for the formation of other types of leases if so desired.

The pin leases above referred to are used principally when the warp is placed in a slasher preparatory to sizing the yarn. However, the invention is also adaptable to be used in the formation of a lease in a warp prepared on a warping machine, and will also be found to be adaptable for the formation of various other types of leases.

The principal object of the present invention is to provide a simple, yet efficient, device for effecting the formation of a lease in a warp whereby the lease may be formed in a simple and expeditious manner, and by a simple series of manipulations.

A further object of the invention is to provide a device for forming warp leases which may be inexpensively constructed.

The present invention contemplates the provision, in a comb or reed, of a dent having a hook portion of novel and peculiar formation for selectively engaging the warp to take a loose therein.

The nature and characteristic features of the invention will be more readily understood from the following description, taken in connection with the accompanying drawing forming part hereof, in which:

Figure 1 is a front elevation of a reed or comb for leasing purposes embodying the main features of the present invention;

Fig. 2 is a face view of one of the dents of the reed or comb shown in Fig. 1, the same being provided with a hook portion of a peculiar formation;

Fig. 3 is a similar view of another of the dents

employed in the reed or comb shown in Fig. 1, the same having its intermediate part formed without any hook portion therein;

Fig. 4 is an enlarged perspective view of the hook portion of one of the dents shown in Figs. 1 and 2;

Fig. 5 is a longitudinal section illustrating, to a certain extent diagrammatically, an early step in the formation of the lease by means of the device of the present invention;

Fig. 6 is a similar view illustrating a later step in the formation of the lease;

Fig. 7 is a horizontal section through a portion of the reed or comb shown in Fig. 1 with the warp threads illustrated in operative relationship with respect thereto, when the first part of the lease is taken as in the step shown in Fig. 5; and

Fig. 8 is a similar view when the second part of the lease is taken as in the step shown in Fig. 6.

It should, of course, be understood that the drawing and description herein contained are illustrative merely, and that various modifications and changes may be made in the structure disclosed without departing from the spirit of the invention.

Referring more particularly to Figs. 1 to 4 of the drawing, there is shown one form of construction of a leasing reed or comb 10 embodying the principal features of the present invention and particularly adaptable for use in the formation of a pin lease in a warp. Said device consists of a suitable frame 11 having side struts 12, and disposed between side struts 12, hook dents 13 and plain dents 14 are suitably spaced in alternate relationship, said dents being rigidly secured at their lower ends in the frame 10 in the usual manner of construction of soldered reeds.

As there shown, each of the dents 13 and 14 comprises a thin flat strip of metal, the dents 13 being each provided intermediate its ends with a hook portion of peculiar formation. At the place where the hook portion is provided, the dent 13 is cut out as at 15, the preferred shape of the cutout being illustrated in Figs. 2 and 4 of the drawing. The cutout is so shaped as to provide a sloping or inclined margin 16 extending from one edge of the dent to a medial point, thence extending downwardly parallel to the side edges of the dent as at 17.

At the lower end of the cutout 15 adjacent the edge of the dent, there is provided an upwardly extending projection 18 which constitutes a hook adapted to function in a manner to be hereinafter more fully set forth to effect the

leasing operation. It should be noted that the hook provided by the upwardly extending projection 18 is disposed entirely in the plane of the dent strip, and does not project beyond either 5 side face thereof.

The other dents 14 are made plain, without any hook portions, and ordinarily the dents will be disposed in spaced relationship, a hook dent 13 alternating with a plain dent 14. It will be 10 noted that by this arrangement, when viewed from the front and rear, the dent spaces will be free and unobstructed, so that as long as the warp extends straight through the dent spaces, none of the ends thereof will be engaged by the hook portion of the dents 13.

The reed or comb formed as aforesaid is preferably open at the top to permit the ready insertion of the warp ends in the proper dent spaces, although it should be noted that, if desired, a cap 20 (not shown) may be placed over the top of the reed or comb, as is sometimes done in devices of this character. In other instances, the reed or comb may have the upper ends of the dents rigidly secured in a manner similar to structure at the bottom. In still other instances, the 25 dents may be supported at their lower ends by suitable springs, as is commonly done in expansion combs which permit the number of dents per inch to be varied to suit the requirement of the user.

The invention relates primarily to the construction and arrangement of the dents, but not to any particular manner in which they may be supported.

In the manipulation of the warp to form a lease 35 therein, the comb or reed may be initially positioned, or shifted sidewise if necessary, to cause the warp ends which are located in each of the dent spaces to bear against one set of faces of the dents, as, for example, in Fig. 7. As illustrated in Fig. 5 of the drawing, one of the supports S¹ of the warp is now lowered from the position shown in dotted lines to that shown in full lines. As the warp is thus lowered, the warp ends in each alternate dent space will be 40 caught by the hooks 18 of the dents 13, and the warp ends which are located in the other alternate dent spaces will pass freely along the smooth faces of the dents 14 against which they bear, and a shed will thus be formed, as shown in Fig. 5, 45 into which may be inserted the first lease rod or cord L¹.

After the lease rod or cord L¹ is inserted in the 50 shed formed as aforesaid, the warp may again be raised by elevating support S¹ to its initial position, as shown in dotted lines in Fig. 6, and the reed may then be shifted sidewise to cause the warp ends, which previously bore against the smooth faces of the dents 14 to now bear against the faces of adjacent dents 13. The support S¹ 55 may then again be lowered from the position shown in dotted lines in Fig. 6 to the position shown in full lines, it being noted that as the support S¹ is thus lowered, the warp ends which 60 encounter the hooks 18 of the dents 13 will be caught in said hooks, and the other warp ends which bear against the faces of the dents 14 will pass downwardly without being engaged by any of said hooks, thereby forming a new shed into 65 which the second lease rod or cord L² may be inserted to complete the lease.

Of course, it will be apparent that instead of raising or lowering the warp as above described, the lease sheds may be formed by leaving the 70 warp supports stationary and causing the comb 75

or reed 10 to be raised and lowered, whereby the hook portions of the dents 13 will selectively engage the warp ends in the same manner as above set forth to form the lease sheds; and it will also be apparent that instead of shifting the reed 5 sidewise, as above set forth, the reed may be left stationary, and the entire body of the warp shifted sidewise but in a contrary direction.

It will be noted that the manipulation for the formation of the lease is quite simple and may be expeditiously performed without requiring any particular skill on the part of the operator; or on the other hand, the device may be readily incorporated in an automatic machine without undue complication.

I claim:

1. A warp leasing device comprising a frame, and a series of dents mounted therein spaced from each other, thereby to provide dent spaces in which the warp is located, said dents comprising thin flat metallic strips, the plane of each dent strip being substantially parallel to the direction of the main body of the warp, and each alternate dent having a warp engaging hook disposed entirely within the plane of the dent strip.

2. A warp leasing device comprising a frame, and a series of dents mounted therein spaced from each other, thereby to provide dent spaces in which the warp is located, said dents comprising thin flat metallic strips, the plane of each dent strip being substantially parallel to the direction of the main body of the warp, each alternate dent having a cutout on one edge of the dent, said cutouts facing in the direction of the main body of the warp, and a warp engaging hook comprising a projection located at one end of the cutout and disposed entirely within the plane of the dent strip.

3. A warp leasing device comprising a frame, and a series of dents mounted therein spaced from each other, thereby to provide dent spaces in which the warp is located, said dents comprising thin flat metallic strips, each alternate dent having a cutout with an inclined margin extending at one end from one edge of the dent to a medial point, and a warp engaging hook comprising a projection located at the other end of the cutout and disposed entirely within the plane of the dent strip.

4. A warp leasing device comprising a frame, and a series of dents mounted therein spaced from each other, thereby to provide dent spaces in which the warp is located, said dents comprising thin flat metallic strips, each alternate dent having a cutout with an inclined margin extending at one end from one edge of the dent to a medial point, thence extending parallel to the edge of the dent, and a warp engaging hook comprising a projection located at the other end of the cutout and disposed entirely within the plane of the dent strip.

5. A warp leasing device comprising a frame, and a series of dents mounted therein spaced from each other, thereby to provide dent spaces in which the warp is located, said dents comprising thin flat metallic strips, each alternate dent having a cutout with an inclined margin extending at one end from one edge of the dent to a medial point, thence extending parallel to the edge of the dent, and a warp engaging hook comprising a projection located at the other end of the cutout and disposed entirely within the plane of the dent strip, and the other alternate dents being plain.

6. A warp leasing device comprising a frame,

and a series of dents mounted therein spaced from each other, thereby to provide dent spaces in which the warp is located, said dents comprising thin flat metallic strips, the plane of each 5 dent strip being substantially parallel to the direction of the main body of the warp, certain of said dents each having a cutout on one edge of the dent, and a warp engaging hook comprising a projection located at one end of the cutout and 10 disposed entirely within the plane of the dent strip, the other end of the cutout being shaped to facilitate the passage of the thread past said end.

7. A warp leasing device comprising a frame, 15 and a series of dents mounted therein spaced from each other, thereby to provide dent spaces in which the warp is located, said dents comprising thin flat metallic strips, certain of said dents each having a cutout with an inclined margin 20 extending at one end from one edge of the dent to a medial point, and a warp engaging hook comprising a projection located at the other end of the cutout and disposed entirely within the plane of the dent strip.

25 8. A warp leasing device comprising a frame, and a series of dents mounted therein spaced from each other, thereby to provide dent spaces in which the warp is located, said dents comprising thin flat metallic strips, certain of said dents 30 each having a cutout with an inclined margin extending at one end from one edge of the dent to a medial point, and a warp engaging hook comprising a projection located at the other end of the cutout and disposed entirely within the 35 plane of the dent strip, and the other dents being plain.

9. A dent for a warp leasing device comprising a thin flat metallic strip having a cutout intermediate its ends, said cutout having an inclined margin extending from one edge of the dent to a medial point, and a warp engaging hook comprising a projection located at the other end of the cutout and disposed entirely within the plane of the dent strip. 5

10. A dent for a warp leasing device comprising a thin flat metallic strip having a cutout intermediate its ends, said cutout having an inclined margin extending from one edge of the dent to a medial point, thence extending parallel to the edge of the dent, and a warp engaging hook comprising a projection located at the other end of 15 the cutout and disposed entirely within the plane of the dent strip.

11. In a warp leasing device, a plurality of dents spaced from each other and each comprising a thin flat metallic strip, the plane of said 20 dent strip being substantially parallel to the direction of the main body of the warp, and certain of said dent strips each having a warp engaging hook disposed entirely within the plane of the dent strip. 25

12. In a warp leasing device, a plurality of dents spaced from each other and each comprising a thin flat metallic strip, the plane of said 30 dent strip being substantially parallel to the direction of the main body of the warp, certain of said dent strips each having a cutout intermediate its ends, and at one end only of said cutout a warp engaging hook comprising a projection disposed entirely within the plane of the dent strip. 35
